Primary Examiner — Kevin K Rudzinski*Assistant Examiner* — Evans David Delesline(74) *Attorney, Agent, or Firm* — Heslin Rothenberg Farley & Mesiti P.C.(57) **CLAIM**

The ornamental design for a wearable band, as shown and described.

DESCRIPTION

FIG. 1 is a front, top perspective view of a wearable band in accordance with the new design;

FIG. 2 is a front, bottom perspective view thereof;

FIG. 3 is a front perspective view thereof;

FIG. 4 is a right side elevational view thereof;

FIG. 5 is a left side elevational view thereof;

FIG. 6 is a rear elevational view thereof;

FIG. 7 is a top perspective view thereof; and,

FIG. 8 is a bottom perspective view thereof.

The long dashed lines in the figures show portions of the wearable band and form no part of the claimed design. The short dashed lines in the figures illustrate stitching and form no part of the claimed design.

1 Claim, 8 Drawing Sheets(56)
